Inventor:
Jay Darling,
by Lester Sargent *Attorney*

UNITED STATES PATENT OFFICE

JAY DARLING, OF WILLIAMSPORT, INDIANA, ASSIGNOR OF ONE-THIRD TO WALTER M. JOYCE AND ONE-THIRD TO J. MERLE DARLING, BOTH OF DETROIT, MICHIGAN

BRICK MASON'S POINTING TOOL

Application filed January 10, 1930, Serial No. 420,211. Renewed September 2, 1931.

The object of my invention is to provide a novel mason's pointing tool which will enable the mason both to carry the mortar and to point the joint between the bricks with great facility.

I attain these and other objects of my invention by the device illustrated in the accompanying drawings, in which,

Figure 1 is a perspective view of my invention;

Fig. 2 is a transverse section through same, a portion of the handle being shown in side elevation;

Fig. 3 is a longitudinal section on line 15 3-3 of Fig. 2;

Fig. 4 is a perspective view of an improved form of my invention adapted for use by either a right or left handed person;

Fig. 5 is a section on line 5-5 of Fig. 4; 20 and

Fig. 6 is a section on line 6-6 of Fig. 4.

Referring to the accompanying drawings, I provide an oblong metal plate 1, having an extension thereof 2, disposed at right angles 25 to plate 1, and having a small extension 3 disposed at right angles to plate 2 and substantially parallel with plate 1.

I provide a suitable handle having a slot 5 to allow the handle to seat over the extension plate 3 to which it is affixed by a suitable screw or other like fastening device 6. I provide suitable screws or other like fastening elements 8 for fastening the lower end 7 of the handle 4 to the plate 1, as shown 35 in Figs. 1 and 2. I provide a long slot 9 extending longitudinally of plate 2 and a short slot 10 near the end of plate 2 farthest distant from the handle extending transversely of that plate.

40 The long slot in the plate 1 is to point the joint between bricks, the short transverse or perpendicular slot is to fill the joint at the end of the brick. The lower plate, table or section 1 of the tool is to carry the mortar 45 so that it will be ready for use. The tool can be used with any kind of a trowel advantageously.

The method of pointing is to hold this tool tight to the building, then using the 50 trowel to place the mortar in the joints. The

tool is a shield against smearing. It keeps the brick clean, forcing the mortar into the joint, thus making speedy and clean work. The handle being in the center of the tool makes it equally efficient for either a right 55 or a left-handed person. It carries sufficient mortar to make a swift and easy application. The slot in each end provides for pointing around window sills or any stone in a brick wall. It is equally good for pointing up chimneys.

Referring to Figs. 4, 5, and 6, there is illustrated an improved form of my invention adapted for use either by a right or left handed person.

65 I provide on opposite ends of the plate 2 like short slots 10 and 11. In place of the L-shaped handle 4, I provide a straight handle 12 fastened to the plate 1 by suitable screws or other suitable fastening devices 6. 70

The handle is used in substantially the same manner as that shown in Figs. 1 to 3 inclusive, as above described, except that by providing the slot 11 in addition to the slot 10 and providing the straight handle 12, 75 the device can be readily reversed for use in either hand.

What I claim is:

1. A mason's pointing tool comprising an oblong plate having an extension plate disposed at right angles to the first plate, a second extension disposed at right angles to the first extension plate, a handle affixed to ends extending between the first plate and the second extension plate, the extension plate having a long slot extending longitudinally of the plate and having a short slot extending transversely of the plate, for the purposes hereinbefore described.

2. In a mason's pointing tool, the combination of an elongated plate having a similar extension plate disposed at right angles to the first mentioned plate and adapted to be used in a vertical position, a handle extending between the two plates and affixed to same, a long horizontal slot in the aforesaid plate and a short vertical slot near the end of said plate distant from the handle.

3. In a mason's pointing tool, the combination of an elongated plate having a similar 100

extension plate disposed at right angles to the first mentioned plate and adapted to be used in a vertical position, a handle affixed to one of the plates, a long horizontal slot in the vertically disposed plate and short vertical slots near the ends of said plate.

4. A mason's pointing tool, comprising an oblong plate having an extension plate disposed at right angles to the first plate, a handle affixed to the first plate, the extension plate having a long slot disposed longitudinally of the plate and having short slots disposed transversely of the plate near the ends thereof.
